UNITED STATES PATENT OFFICE.

JOHN T. VAN DILLEN, OF ST. LOUIS, MISSOURI.

ELECTRIC TIME-LOCK.

No. 806,942.

Specification of Letters Patent.

Patented Dec. 12, 1905.

Application filed August 17, 1904. Serial No. 221,155.

To all whom it may concern:

Be it known that I, JOHN T. VAN DILLEN, a citizen of the United States, and a resident of St. Louis, Missouri, have invented certain 5 new and useful Improvements in Electric Time-Locks, of which the following is a specification, containing a full, clear, and exact description, reference being had to the accompanying drawings, forming a part hereof. 10 My invention relates to improvements in electric time - locks; and it consists of the novel features herein shown, described, and claimed.

In the drawings, Figure 1 is a horizontal 15 section through the safe and time-lock, taken substantially on the lines 1 1 of Fig. 3. Fig. 2 is an enlarged sectional detail on the line 2 2 of Figs. 1 and 3. Fig. 3 is a rear elevation of the safe-door, with the clock mechanism removed, as seen looking in the direction indicated by the arrows 3 in Figs. 1 and 2. Fig. 4 is a view in elevation of the rear side of 20 the clock mechanism, upon an enlarged scale and looking in the direction indicated by the arrows 4 in Figs. 1 and 5. Fig. 5 is an edge view of the parts shown in Fig. 4 as seen looking in the direction indicated by the arrow. Fig. 6 is a front elevation of the clock mechanism as seen looking in the direction indicated by the arrow 6 in Figs. 1 and 5 25 with the casing removed. Fig. 7 is a detail perspective of the brush mechanism, parts being broken away to economize space. Fig. 8 is a sectional view of the handle for making 30 the electrical connection, unlocking the door, and removing the door, the electric circuit 35 being shown in diagram.

Referring to the drawings in detail, the body 10 of the safe is spherical in form and is 40 constructed of cast-steel cored to form the chamber 11 and to form the internal boss 12. The door-opening is bored through the boss 12 and has a continuous screw-thread 13. The door 14 has an exterior screw-thread 15 45 to fit the screw-thread 13, and the outer face of the door is a segment of a sphere, so that when the door is secured into position the spherical form of the safe is completed. A chamber 16 is formed from the rear side of 50 the door to contain the time-lock mechanism. The locking-bolts 17 are mounted in the bearings 18, formed from the periphery of the door 14, and expansive coil-springs 19 are mounted in the bearings 18 behind the 55 bolts 17 to force the bolts outwardly into the seats 20 to form the body of the safe, so that

when the bolts are in their normal positions the door 14 cannot be unscrewed. The inner ends of the bearings 18 are reduced in size to form shoulders against which the inner ends of the springs 19 rest, and the inner ends of the bolts 17 are reduced in size to operate through the reduced portions of the bearings, said bolts extending into the chamber 16. Heads 21 are placed upon the inner 60 ends of the bolts to form stops and engage the wall of the chamber and resist the tension of the spring 19. Ears 22 extend inwardly from the bolts 17 beyond the heads 21 into the chamber 16, there being openings 70 23 through said ears. An electromagnet 24 is mounted upon the frame 25, secured to the wall of the chamber 16, and the armature 26 is mounted upon a lever 27, pivoted to the frame 25, there being a stop-arm 28 behind 75 the lever 27 to limit its outward motion. Arms 29 extend both ways from the armature-lever 27 and engage the inner ends of the bell-crank levers 30, the outer ends of 80 said levers operating in the openings 23 of 85 the ears 22, so that the tension of the springs 19 will hold the armature normally away from the magnet and against the stop-arm 28, so that when the magnet is energized and the armature attracted the tension of the springs 19 will be overcome and the bolts 17 withdrawn, so that the door may be unscrewed 90 and removed from the safe. One end 31 of the magnet-wire is attached to the door 14 by a screw 32. The other end 33 of the mag- 95 net-wire is attached to the contact-plate 34, said plate being insulated from the metal of the door. A second contact-plate 35 is insulated from the metal of the door and mounted upon the opposite side of the magnet from 100 the first contact-plate. A plug 36 is inserted through the door, said plug being insulated from the metal of the door by the sleeve 37, and said plug being headed down upon both ends, so that it cannot be removed. A wire 105 38 leads from the plug 36 to the contact-plate 35. Ledges 39 are inserted in the chamber 16 upon opposite sides of the magnet 24, and buttons 40 extend from the ledges. A disk 41 is provided large enough to cover the inner face of the door 14. A supporting-plate 110 consisting of the central portion 42, the intermediate portions 43, extending backwardly from the ends of the central portion, and the end portions 44, extending outwardly from the inner ends of the intermediate portions and having buttonholes 45, is secured

to the face of the disk 41, there being a central opening 46 in said disk and the central portion 42 of the supporting-plate extending across this central opening. The buttons 40 engage in the buttonholes 45 to hold the disk 41 in position. A buttonhole 47 is formed in the center of the central portion 42 of the supporting-plate. The central post 48 of the clock passes through this buttonhole 47, so as to connect the clock to the disk 41. Contact-plates 49 and 50 are mounted and insulated back of the supporting-plate in position to engage the contact-plates 34 and 35. A ring 51 is mounted upon insulation-plugs 15 around the clock and connected to the contact-plate 49 by the wire 52. A second ring 53 is mounted upon insulation-plugs around the clock, and a wire 53^a connects this ring to the contact-plate 50. A brush 54 is mounted upon a plug of insulation carried by the outer face of the clock-shell and engages the ring 51, and a second brush 55 is insulated in position to engage the ring 53. Spring-arms 20 56 and 57 extend from the brushes 54 and 55, there being a plate 58 extending laterally from the arm 56 over the end of the arm 57, said plate 58 being normally out of contact with the arm 57. A lever 59 is pivotally mounted in position to engage the plate 58 at 25 one end, and the other end of the lever is connected to the alarm mechanism of the clock by the connecting-rod 60, so that when the time comes for the alarm to go off the lever 59 is operated to press the plate 58 against the arm 57 and close the circuit.

The clock mechanism shown is of that type which is wound by rotating the casing of the clock, and the rings 51 and 53 provide means of keeping up the electrical connection while the casing of the clock is rotating, the brushes 40 54 and 55 being carried by the clock as it rotates and the rings 51 and 53 being stationary. A handle 61 has nipples 62 and 63, adapted to be inserted into the openings 44 in the door and 65 in the plug 36 for screwing the door in and out. An electric terminal 66 is mounted in the nipple 62 and insulated therefrom, and a second terminal 67 is mounted in the nipple 63. A wire 68 leads 45 from the battery 69 to the terminal 67, and a second wire 70 leads from the battery to the terminal 66, so that when the handle is inserted into position the circuit is completed, and if the clock mechanism has operated the plate 58 into contact with the arm 57 the electromagnet will be energized to withdraw the bolts 17, so that the door may be removed from the safe.

One of the principal uses for which this 60 safe is intended is that of a strong box to be used in transporting valuables from one place to another. When the door is inserted, the safe becomes merely an iron ball to be rolled around and easily transported.

65 In order to keep the contents of the safe

from injuring the clock mechanism, a casing 71 is placed over the clock.

It is obvious that the door cannot be removed from the safe except by completing the circuit and energizing the electromagnet 70 and that this can only be done at the time the circuit is closed between the arms 56 and 57.

I claim—

1. In an electric time-lock: the spherical body 10 constructed of cast-steel and cored to form the chamber 11 and the internal boss 12; there being a door-opening through the boss 12; a continuous screw-thread 13 in said door-opening; the door 14 having an exterior screw-thread to fit in the screw-thread 13; the outer face of the door being a segment of a sphere to match the spherical form of the body; an electric time-lock mechanism controlling the operation of the door; and 75 means of operating the electric time-lock mechanism from the outside; said means comprising an insulated plug; an electric connection between the body of the safe and the electric time-lock mechanism; an electric connection between the plug and the electric time mechanism; a handle having nipples one to engage the body of the door, and one to engage the plug; said nipples being insulated from each other; and a battery 80 connected to said nipples; substantially as specified. 90

2. In an electric time-lock: the combination with a suitable safe - body and a door adapted to be screw-seated in the body; there 100 being a chamber in the rear face of the door; of locking-bolts mounted in bearings formed from the periphery of the door and adapted to pass into seats in the body of the safe; expansive coil-springs mounted in the bearings 105 behind the bolts to move the bolts into the seats; an electromagnet mounted in the chamber of the door; an armature mounted upon a lever pivoted to the frame in position to be operated by the electromagnet; said armature 110 being connected to the locking-bolts, so that when the armature is energized, the bolts will be withdrawn from their locked positions; and means for energizing the electromagnet from the outside of the safe; an insulated plug through the wall of the safe; the electromagnet being connected to the plug and to the body of the safe; a handle having nipples to engage the body of the door and the plug; said nipples being insulated from each other; and a battery connected to said nipples; substantially as specified. 115

3. In an electric time-lock: the combination with a safe, and a door adapted to be seated in the safe; of locking-bolts slidingly 125 mounted in the door in position to engage in seats in the body of the safe; an electromagnet; an armature for the electromagnet connected to the locking-bolts, so that when the magnet is energized, the bolts are withdrawn; 130

clock mechanism for opening and closing the electromagnet-circuit inside of the safe; and means for opening and closing the circuit outside of the safe; substantially as specified.

- 5 4. In an electric time-lock: the combination with a safe-body, and a door adapted to be seated in the safe-body, of locking-bolts slidingly mounted in the door to engage in seats in the body; electromagnet mechanism 10 for operating the locking-bolts; said electromagnet mechanism being mounted in a chamber in the rear face of the door; a disk for covering the chamber; a clock mounted upon the disk; rings mounted upon insulation-plugs 15 around the clock; a brush mounted upon insulation carried by the clock-shell in position to engage one of the rings; a second brush

mounted upon insulation carried by the clock-shell in position to engage the other ring; spring-arms extending from the brushes; 20 a plate extending from one of the spring-arms over the other spring-arm; and means for pressing said plate downwardly upon the spring-arm to close the circuit; said means being controlled by the clock mechanism; 25 substantially as specified.

In testimony whereof I have signed my name to this specification in presence of two subscribing witnesses.

JOHN T. VAN DILLEN.
